LIFT PLATFORM TRUCK

Donald S. Andrews, Rumson, N. J., and John Ronald Wyllie, New Canaan, Conn., assignors to Andrews Crane Corporation, New York, N. Y., a corporation of Delaware

Application June 9, 1930, Serial No. 460,050

12 Claims. (Cl. 280—33.2)

Our invention relates to trucks which are adapted to be used about factories, docks, warehouses, etc., where it is necessary to move in restricted spaces and over irregular surfaces, such as are formed by ramps arranged at an angle to the floor or ground, and which are commonly known as warehouse trucks, and more particularly to lift-platform trucks for use in loading freight onto and unloading it from carrying vehicles, such as box cars, ships, etc.

In an application filed by us January 21, 1927, Serial No. 165,010, there is disclosed and claimed a method of handling freight in which the goods to be shipped are placed in large containers having permanent supports so constructed that while supported on the floor, they may be engaged by a lift-platform truck, freed from the floor and thereby transferred to the control of the truck, carried to any desired place and there deposited, all without manual handling as required by present methods. The present invention was devised particularly for use in this method, although in some of its features it has a wider application.

The primary object of the invention is to facilitate the handling of merchandise in such containers by mechanical means, that is, in a way to avoid manual handling, to the end that the loaded and unloaded containers may be mechanically engaged with and disengaged from the truck, and the truck may be manipulated to move the container into a confined space and deposit it therein or remove it from such a space.

Another object of the invention is to effect the movement of loads in an efficient manner over irregular surfaces such as are encountered at freight depots and docks, for example, where the load must be moved over an upwardly or downwardly inclined ramp.

Another object of the invention is to provide means whereby a lift-platform may be projected beneath a container when it is approached from an angle to a horizontal plane or from an angle to a vertical plane.

Another object of the invention is to so relate the power driving means and the load-carrying means as to prevent the load from decreasing the tractive effort of the driving means.

Another object of the invention is to facilitate effective control of the apparatus by the operator.

The invention consists in the means hereinafter described and illustrated in the annexed drawings, and particularly set forth in the claims.

The invention is capable of embodiment in a wide variety of forms but the best forms in which we have contemplated applying the principles

thereof are shown in the accompanying drawings in which,

Fig. 1 is a side elevation of the preferred form of truck, with the front end of the trailer member broken away.

Fig. 2 is a top plan view thereof.

Fig. 2a is a top plan view of the tapered front end of the lift-platform.

Fig. 3 is a vertical section of the trailer member of the truck, showing a lift-platform and mechanism for elevating it.

Fig. 4 is a diagrammatic plan view of the tractor member of the truck in two positions, illustrating a characteristic movement of the draw-bar of the truck.

Fig. 5 is an enlarged fragmentary section of the draw-bar connection with the trailer, taken on line 5—5 of Fig. 2.

Fig. 6 is a perspective view of a loaded platform for the handling of which, or structures of the same general characteristics, this invention is designed.

Fig. 7 illustrates, in plan, a box car partially loaded and in the course of loading, illustrating the utility of one of the features of the truck.

Fig. 8 is a fragmentary plan view illustrating how the trailer member of the truck may be inserted beneath a loaded container while in a confined space in a box car.

Fig. 9 illustrates two steps in unloading a container from a box car after the container has been raised from the floor onto the lift-platform.

Fig. 10 is a view similar to Fig. 9 illustrating two final steps of manipulating a loaded container before removing it from a car.

Fig. 11 is a side elevation of a tractor member slightly modified as to the construction of the draw-bar in respect to its connection with the tractor member, and with a coupling means adapted to be connected with an eye on the adjacent end of a wheeled container or with such an eye mounted on the rear end of the trailer member shown in Figures 1 and 3.

Figs. 12 and 13 are diagrammatic views illustrating the utility of certain features of the trailer member, and the relation thereof to the tractor.

Our invention is designed for use in handling freight by a container system, adapted to the present railroad equipment including box cars having a floor width of from 8 feet to 8 feet 6 inches with door openings about 6 feet wide. While the value of the container system has been long recognized and it has been used to a considerable extent in various forms, prior to our invention no system had been devised or attempted in which present

railroad equipment was utilized. For the most successful operation of such a system the containers should be large and of a size such that a certain number of units will substantially fill the 5 floor space of a box car. It will be appreciated that where large containers are employed of a size that a plurality will fill substantially the entire floor space of a box car, the relatively small spaces available for manipulating them into place 10 by purely mechanical means presents a very difficult problem, and prior to our invention there was no apparatus devised, so far as we have discovered, which could be used to place such containers or remove them from the restricted space contemplated by us. Prime requisites of a truck 15 which will operate successfully to perform the described function is that it shall be able to move the container on an axis within itself, and that it shall be able to impart considerable movement 20 to the container under its control with only slight bodily motion of itself.

This application is a continuation in part of our application Serial No. 197,033, filed June 7, 1927.

25 We have devised a number of embodiments to effect the desired movements of the containers, but the form now to be described is, so far as we have discovered up to the present time, the most efficient. We will first set out the exact construction and dimensions of this embodiment, and then point out the considerations which would govern departures from such construction and dimensions.

30 Referring to the drawings in detail, the truck is composed of a tractor member 1, and a trailer member 2, articulated to the tractor member. The tractor member comprises a frame 3 of a width of approximately 3 feet 6 inches and of a length approximately 5 feet. This frame is supported at its front end by two traction wheels 4, 4', which are preferably fixed on axles having interposed differential mechanism of any desired form. The rear end of the tractor frame is supported by a single steering wheel 5 mounted for steering movement about a vertical axis through 35 an arc not less than about 170°. The axis of the steering wheel is approximately 3 feet from the axis of the traction wheels, and the rear end of the tractor frame extends approximately 1 foot 40 to the rear of the axis of the steering wheel. The tractor frame carries a tiller handle 6 to give steering movement to the steering wheel, and is provided with the usual means appurtenant to a tractor including means for furnishing motive power. A suitable platform 7, adapted to support an operator, is connected with the front end of the frame 3, the location of this platform being selected for reasons hereinafter stated. A 45 draw-bar 8 is connected with and extends forwardly from the front end of the frame 3, the connection being preferably a pivotal connection on a horizontal axis by means of a bolt 9 passing through brackets 10, connected rigidly with the frame, and through the bifurcations 11 of the 50 rear end of the draw-bar, so that the draw-bar is rigid in a horizontal plane but is capable of pivotal motion in a vertical plane. The front end of the draw-bar is provided with means complementary to means on the trailer member for 55 coupling the trailer member and tractor member together, such complementary means being hereinafter referred to as coupling means. The length of the draw-bar in this embodiment is such that the coupling means is approximately 6 feet from 60 the axis of the traction wheels.

The trailer member 2 comprises a frame 12, preferably of the same width as the tractor frame and about 6 feet in overall length, supported by rolling-supporting means which may take various forms and the elements of which may be variously related to each other and to the frame. As illustrated, such rolling-supporting means 5 comprises load-supporting wheels 13 mounted on a horizontal axis on opposite sides of the longitudinal axis of the frame, such load-supporting 10 wheels being placed so that when a container is mounted thereon they will be substantially underneath, or slightly rearward, of the center of the load; for a container of the size contemplated by us the location of the axis of the load-supporting 15 wheels would be approximately 4 feet from the rear end of the trailer frame. The rear end of the trailer frame is supported by two casters 14 arranged on opposite sides of the longitudinal axis of the trailer frame, which permit 20 the tractor member to push and pull the trailer, and also to swing it laterally on the load-supporting wheels, the casters conforming to any motion imposed upon the trailer. A single caster 25 15 is mounted in the extreme front end of the trailer frame in substantially the longitudinal axis thereof. Preferably the elements of the rolling-supporting means are so related that, when on a level surface, the trailer will be supported by the load-supporting wheels and casters 14, 30 or by the load-supporting wheels and caster 15 (see Fig. 3) this being effected by so mounting the caster 15 that the lower periphery is above a plane tangent to the load-supporting wheels 13 and the casters 14 at their points of contact 35 with the supporting surface, as clearly indicated in Fig. 3.

The trailer frame supports a lift-platform 16 mounted for vertical movement thereon, such vertical movement being effected by well-known 40 means. As shown, the construction which enables the platform to be elevated consists of cam plates 17 depending from the platform, which are engaged by rollers 18 mounted on a longitudinally movable actuating frame 19, which is reciprocated by an electric or other suitable motor 20, under control of the operator from his position on the platform 7. The actuating frame is controlled through the medium of a thrust screw 21 connected to the actuating frame, which is 45 extended and retracted by means of suitable gearing operated by the motor, all of which is old in the art.

The sides of the frame of the trailer member at the front end are tapered and the sides of the lift-platform are correspondingly tapered as indicated at 22, Fig. 2a. The purpose of thus tapering the lift-platform is to enable it to be inserted beneath a platform container, as clearly indicated in Fig. 8. The extent of this tapering 55 will therefore be governed by the particular conditions under which the device is used. As shown herein the length of the tapered side is more than three-fourths of the width of the lift-platform, and the angular relation of such tapered 60 sides to the longitudinal axis of the trailer member is less than 30°. The end of the tapered portion of the lift-platform is beveled downwardly as indicated at 23, the beveled portion, as shown, extending more than a foot from the end of the 65 frame. The rear edge of the trailer frame is provided with an upstanding flange or shoulder 24 adapted to be engaged by the end of the container to prevent its further movement rearwardly. 70 75

As above stated the front end of the draw-bar 8 is coupled with the rear end of the trailer member, the coupling shown consisting of a ball connected with the trailer which enters a socket formed at the end of the draw-bar as clearly shown in Fig. 5. As shown in Fig. 11 the coupling consists of a hook on the end of the draw-bar entering an eye on the member to be connected thereto. Both of these connections provide a universal joint. The best embodiment of the invention contemplates that the pivotal connection between the end of the draw-bar and the trailer member shall be so located that the draw-bar may, in one extreme position, lie at an angle less than 90° to the longitudinal axis of the trailer. This extreme position is illustrated in Fig. 7, and the purpose thereof will be herein-after described. In order to secure this relation in the embodiment shown in Figs. 1 to 3, the coupling means of the draw-bar and the trailer member are positioned about 6 inches rearwardly of the rear end of the trailer frame.

Characteristic movement of the coupling means on the end of the draw-bar 8 is illustrated in Fig. 4. In the construction shown the center about which the tractor turns when the steering wheel is set for turning movement is the intersection of a line extended through the axis of the traction wheels and a line extended through the axis of the steering wheel at that particular setting. When the steering wheel is set to give the sharpest turn to the tractor member, the center about which the end of the draw-bar swings is in line with the axis of the traction wheels just outside one of the traction wheels, which results in the movement of the coupling means of the draw-bar on an arc y whose radius is x . Hence it will be appreciated that the turning axis of the traction member ranges between infinity (that is, movement in a straight line forwardly or backwardly), and points just outside of the traction wheels, so that the coupling member at the end of the draw-bar may be caused to move forwardly or backwardly, or to describe an arc about any center on either side of the frame ranging between infinity (when the steering means is set for the frame to move in a straight line along its longitudinal axis) and points near the sides of the frame; in other words, the traction member may move in a straight line or any arc between one of great radius and a very short radius. When the steering wheel is set for the minimum turning radius the coupling means will move in an arc whose radius is greater than 6 feet, and the frame of the tractor member will swing about a point just outside one of the traction wheels, so that there is lateral motion of the frame with very slight longitudinal motion thereof.

Our invention contemplates the use primarily, of containers supported on an inverted U-shaped platform of well known form, illustrated in Fig. 6, consisting of a central base and side supports or flanges by which the container is supported above the floor to permit the entrance therebeneath of a lift-platform whereby, on elevating the platform, the load is transferred from the floor to the truck. The size of the container adapted for use with our trucks may be varied, but we prefer to employ containers as large as possible, which may be used to substantially fill the floor space of an ordinary box car with a plurality thereof and which it is possible to pass through the doors thereof and manipulate into place by mechanical means, this size being about 90 inches long and

about 42 inches wide, and of any height less than the height of the door openings, ten of which will occupy substantially the entire floor area of a box car. Such containers, when loaded, may weigh upwards of five tons. Four of such containers may be placed in either end of a box car, and two in the center of the car, transversely thereof, facing the door opening. It is a very simple matter to remove the two containers facing the door opening, and little difficulty is experienced in placing or removing the two containers in the ends of the car. But the insertion or removal of the other four containers in the spaces just inside the door, by mechanical means, presents a very difficult problem, requiring the rotation of the container at one time on an axis within itself, and at another time a movement of the container nearly in a straight line for a considerable distance. Our invention effectively provides for the required movements, and the utilization of the characteristic features thereof will now be set out in an explanation of the steps required in removing a container c from a box car (see Figs. 8, 9, and 10) while containers a , b , d , e , f , g , and h remain in place.

Operation.—In the operation of removing container c from the car, the operator directs the front end of the trailer to a position opposite the end of the container and then sets the steering wheel 5 to give the tractor member a sharp turning radius which moves the trailer in a wide arc, causing the front tapered end thereof first to pass between the supports of the container, whereupon further movement will cause the lift-platform to move beneath the container until the flange 24 engages the end of the container. The lift-platform is then operated to lift the container free of the floor. The steering wheel is then set to cause the tractor member to move from the position shown in full lines of Fig. 9 to the position shown in dotted lines. It may be observed from the two positions shown that, because of the long draw-bar and short turning radius of the tractor member the container may be moved into the opening between the doors in a straight line so as to avoid being jammed between the adjacent container d and the side of the car, while at the same time the rear end of the tractor frame has moved almost laterally into the door opening, thus avoiding contact with the container f and the edge of the door opening. The swinging motion of the tractor member is continued in the same general direction until the parts reach the position shown in full lines in Fig. 10. The steering wheel is then operated to cause turning motion in the opposite direction, which causes the container to turn on axes within the boundaries of the trailer frame while it is advancing toward the door opening.

The operation required to place container d in position when containers a , b and c are in place is the reverse of the operation described above for removing container c . The truck is moved forwardly to push the container over the ramp and through the car door, the steering wheel 5 meanwhile being turned so that, as the inner rear corner of the container approaches closely to the side of container c and the outer side of container d has come nearly in contact with the edge of the door opening, the axis of the draw-bar approaches a position sharply at an angle to the longitudinal axis of the trailer member. When it has arrived at this position, the steering wheel is suddenly turned in the opposite direction, i. e., to the left, so that the turning axis 75

is very near the left-hand side of the tractor frame. The tractive effort of the traction wheels then causes the end of the long draw-bar to swing about said axis, and the length of the draw-bar is such that there is no substantial forward motion of the container and the container is rotated on the load-supporting wheels 13 until the longitudinal axis of the container is alined with the side of the car, whereupon, by reversing the position of the steering wheel 5, the container may be moved into the space between container c and the side of the car. If desirable or necessary, by properly steering the tractor member, the draw-bar may be caused to take a position at right-angles (or less than a right-angle) to the longitudinal axis of the trailer member when the container d is jammed between container c and the edge of the door opening, as when the rear inner end of the container has come into contact with the side of container c and the outer side of the container d has come into engagement with the side of the door opening, as shown in Fig. 7, whereupon, a direct forward motion of the tractor member will rotate the container, break the jam, and aline it with the space into which it is to be placed. Thereafter, proper steering movement of the tractor member will move the container into the desired place. These movements are possible because of the very short turning radius of the tractor member, and the flat arc described by the end of the long draw-bar.

As above indicated, it is desirable that the construction of the parts be such that, at certain times, the draw-bar shall be permitted to lie, in relation to the longitudinal axis of the trailer, at an angle of only a little greater than 90°, or even less. In the form above described this may be accomplished by a narrow draw-bar coupled to the trailer at a suitable distance from the rear of the trailer frame. It might also be accomplished by so arranging the trailer frame with respect to the draw-bar that the trailer frame would, in part, overlie the draw-bar in extreme position, in which case a narrow draw-bar would not be required.

The purpose of placing the operator's stand or platform 7 at the front of the tractor member is to enable the operator to more readily sense lateral motion of the tractor member and observe the effect of his manipulation.

The purpose of tapering the front end of the trailer has already been stated. The purpose of the downward bevel of the tapered position is to enable the trailer to be projected beneath a container when approached at an angle to a horizontal plane, as indicated in Fig. 13.

Figs. 12 and 13 illustrate the utility of the particular form of rolling supporting means for the trailer above described. The floor or ground over which such loads must be moved often have depressions or angularly related surfaces. For example, at tidewater, loads must be moved from dock to ship and vice versa, up and down ramps which are variously inclined to the floors of the dock and ship, and not uncommonly containers are supported at the upper edge of an inclined ramp, as illustrated in these figures. Where a horizontal surface thus meets an inclined surface serious difficulties are encountered with trucks of ordinary construction. One such difficulty is that in passing up an inclined ramp, especially one sharply inclined, the forward end of the truck or the container thereon will engage the ramp and stop further movement. This

difficulty is entirely avoided by providing a roller, such as caster 14, at the forward end of the truck, which engages the inclined surface; and this feature is especially applicable to lift-platform trucks now in general use as well as to the trailer member disclosed herein, and greatly increases their utility.

The caster 15 has an additional important function when used in combination with the two rear casters 14, which together provide a stable support for the trailer and its load while moving onto an inclined surface and while the central supporting wheels are lifted clear of the supporting surface, as clearly shown in Fig. 12. In use, surface conditions will vary greatly, but the rolling supporting means herein disclosed provides stable support for the trailer at not less than three points under all conditions.

Another feature of the rolling supporting means used for the trailer, when employed with a draw-bar pivoted to the tractor on a horizontal axis, is that the load is always supported on the trailer alone, or independently of the tractor, thus removing all strain from the tractor and preventing all interference with its tractive effort.

Fig. 11 shows a modification of the draw-bar connection with the tractor frame in that the bifurcations of the rear end of the draw-bar are more widely separated and are pivoted to the outer faces of the tractor frame, as indicated at 25, with a view to increasing the strength of the connection between draw-bar and tractor frame in a lateral direction. This figure illustrates another modification of our invention in which containers having permanent rolling-supporting means are adapted to co-operate with the tractor member, and a trailer member is dispensed with, the rolling-supporting means for the container consisting of centrally arranged load-supporting wheels and casters at opposite ends, similar to the arrangement of the rolling-supporting means on the trailer.

In both of the embodiments of the tractor member illustrated, the traction wheels are not adapted to be steered, for which reason the center of the shortest turning radius is outside the traction wheels. It is obvious that these traction wheels might be constructed for steering movement in which case the center of the shortest turning radius might be brought to a point within the boundaries of the tractor frame.

The specific embodiment of our invention described is designed to meet the special situation presented by the ordinary box car used in present railroad equipment. It is therefore obvious that if more space is available for manipulation the special features described may be modified in various ways,—in the character of the traction means and the steering means and their relation to each other, the length of the tractor and trailer frames and length of the draw-bar. The principal characteristics of a device which will perform the required functions involve a tractor member having a comparatively long draw-bar with steering means that will give a wide sweep to the coupling means at the end of the draw-bar compared to the bodily motion of the tractor frame, with the capacity to swing the container on axes within the boundaries of the trailer frame. While in the preferred form above described the draw-bar is of such length that the distance of its coupling means at the free end from the axis of the traction wheels is approximately twice the length of the wheel base, useful results are obtained when this distance is ap-

proximately not more than two times, and not less than one and one-half times the length of the wheel base.

What we claim is:

5. 1. A warehouse tractor member comprising a frame, traction wheels mounted near the front end of the frame, dirigible rolling supporting means near the rear end of the frame and steering means therefor adapted to give directed movement to the rear end of the frame along the longitudinal axis of the frame or at any angle thereto up to approximately 50° on either side of said longitudinal axis, and a draw-bar connected to and extending forwardly from said frame and having coupling means at its free end, the length of the draw-bar being such that the distance of the coupling means from the axis of the traction wheels is greater than the distance of said axis from the rear end of the frame.
10. 2. A warehouse tractor member comprising a frame, traction wheels supporting the front end of the frame, a steering wheel supporting the rear end of the frame adapted to turn through an angle of at least 100° so as to give directed movement to the frame in directions ranging between a right line along the longitudinal axis of the frame to 50° on either side of said axis, the distance between the axis of the traction wheels and the axis of the steering wheel being approximately three feet, and a draw-bar connected to and extending forwardly from the frame and having a coupling at its free end of such length that the distance of the coupling from the axis of the traction wheels is approximately twice the wheel base.
15. 3. A warehouse tractor member comprising a frame, rolling supporting means for the front and rear ends of the frame including traction wheels, a draw-bar rigid with the frame in a horizontal plane and extending forwardly therefrom and having coupling means at its free end, the length of the draw-bar being such that the distance of the coupling means from the axis of the forward rolling supporting means is approximately not more than two times, and not less than one and one-half times, the length of the wheel base, and means connected with the rolling supporting means to control the movement of the tractor member, whereby the coupling means may be caused to move forwardly or backwardly or to describe an arc about any center on either side of the frame ranging between infinity and points near the sides of the frame.
20. 4. A warehouse tractor member comprising a frame, traction wheels supporting the front end of the frame, and dirigible rolling supporting means supporting the rear end of the frame, a draw-bar rigid with the frame in a horizontal plane extending forwardly therefrom and having coupling means at its free end, the length of the draw-bar being such that the distance of the coupling means from the axis of the traction wheels is more than one and one-half times the length of the wheel base, and means connected with the dirigible rolling supporting means to control the movement of the tractor member, whereby the coupling means may be caused to move forwardly or backwardly or to describe an arc about any center on either side of the frame ranging between infinity and points near the sides of the frame.
25. 5. A warehouse tractor member comprising a frame, traction wheels supporting the front end of the frame, a single steering wheel supporting the rear end of the frame, a draw-bar rigid with the frame in a horizontal plane extending forwardly therefrom and having coupling means at its free end, the length of the draw-bar being such that the distance of the coupling means from the axis of the traction wheels is more than one and one-half times the length of the wheel base, and means connected with the steering wheel to control the movement of the tractor member, whereby the coupling means may be caused to move forwardly or backwardly or to describe an arc about any center on either side of the frame ranging between infinity and points near the sides of the frame.
30. 6. The combination specified in claim 5 in which the axes of the traction and steering wheels are approximately three feet apart.
35. 7. The combination specified in claim 5 in which the traction frame extends approximately one foot forwardly and rearwardly beyond the axes of the traction and steering wheels.
40. 8. A warehouse tractor member comprising a frame, traction wheels supporting the front end of the frame, a draw-bar connected to and extending forwardly from the frame and having coupling means at its free end of such length that the distance from the coupling means to the axis of the traction wheels is greater than the distance between said axis and the rear end of the frame, and dirigible rolling supporting means supporting the rear end of the frame with controlling means therefor whereby the coupling means may be caused to move forwardly or backwardly along the longitudinal axis of the frame or to describe an arc about any center on either side of the frame ranging between infinity and points near the sides of the frame.
45. 9. In a lift-platform truck, a tractor member having traction wheels at its front end and dirigible rolling supporting means at its rear end, a draw-bar attached to the tractor member and extending forwardly therefrom, a trailer member having a lift-platform, a pivotal connection between the forward end of the draw-bar and the rear end of the tractor member devoid of substantial lost motion in a direction at right-angles to the draw-bar, load-supporting wheels intermediate the ends of the trailer member and rolling supporting means at the rear end thereof adapted to conform to any movement imposed upon it by the tractor member through the draw-bar, the length of the draw-bar from the axis of the traction wheels to its pivotal connection with the trailer member being greater than the wheel base of the tractor member.
50. 10. A trailer member for a truck, comprising a frame having a centrally arranged coupling eye at its rear end, load-supporting wheels intermediate its ends and casters supporting the rear end, and a lift-platform mounted on the frame tapered at its front end, the length of the tapered sides being more than three-fifths of the width of the frame and arranged at an angle to the longitudinal axis of the trailer frame of between 20° and 50°.
55. 11. A trailer member for a truck comprising a frame having a coupling means at its rear end, load supporting wheels intermediate its ends, rolling supporting means for the rear end of the frame, and a lift-platform mounted on said frame having its front end tapered downwardly.
60. 12. In a lift-platform truck, a tractor member having traction wheels at its front end and dirigible rolling supporting means at its rear end, a draw-bar attached to the tractor member and extending forwardly therefrom, a trailer mem-

the frame in a horizontal plane extending forwardly therefrom and having coupling means at its free end, the length of the draw-bar being such that the distance of the coupling means from the axis of the traction wheels is more than one and one-half times the length of the wheel base, and means connected with the steering wheel to control the movement of the tractor member, whereby the coupling means may be caused to move forwardly or backwardly or to describe an arc about any center on either side of the frame ranging between infinity and points near the sides of the frame.

6. The combination specified in claim 5 in which the axes of the traction and steering wheels are approximately three feet apart.

7. The combination specified in claim 5 in which the traction frame extends approximately one foot forwardly and rearwardly beyond the axes of the traction and steering wheels.

8. A warehouse tractor member comprising a frame, traction wheels supporting the front end of the frame, a draw-bar connected to and extending forwardly from the frame and having coupling means at its free end of such length that the distance from the coupling means to the axis of the traction wheels is greater than the distance between said axis and the rear end of the frame, and dirigible rolling supporting means supporting the rear end of the frame with controlling means therefor whereby the coupling means may be caused to move forwardly or backwardly along the longitudinal axis of the frame or to describe an arc about any center on either side of the frame ranging between infinity and points near the sides of the frame.

9. In a lift-platform truck, a tractor member having traction wheels at its front end and dirigible rolling supporting means at its rear end, a draw-bar attached to the tractor member and extending forwardly therefrom, a trailer member having a lift-platform, a pivotal connection between the forward end of the draw-bar and the rear end of the tractor member devoid of substantial lost motion in a direction at right-angles to the draw-bar, load-supporting wheels intermediate the ends of the trailer member and rolling supporting means at the rear end thereof adapted to conform to any movement imposed upon it by the tractor member through the draw-bar, the length of the draw-bar from the axis of the traction wheels to its pivotal connection with the trailer member being greater than the wheel base of the tractor member.

10. A trailer member for a truck, comprising a frame having a centrally arranged coupling eye at its rear end, load-supporting wheels intermediate its ends and casters supporting the rear end, and a lift-platform mounted on the frame tapered at its front end, the length of the tapered sides being more than three-fifths of the width of the frame and arranged at an angle to the longitudinal axis of the trailer frame of between 20° and 50°.

11. A trailer member for a truck comprising a frame having a coupling means at its rear end, load supporting wheels intermediate its ends, rolling supporting means for the rear end of the frame, and a lift-platform mounted on said frame having its front end tapered downwardly.

12. In a lift-platform truck, a tractor member having traction wheels at its front end and dirigible rolling supporting means at its rear end, a draw-bar attached to the tractor member and extending forwardly therefrom, a trailer mem-

ber having a lift-platform, a pivotal connection between the forward end of the draw-bar and the rear end of the trailer member devoid of substantial lost-motion in a direction at right angles to the draw-bar, the length of the draw-bar being such that the distance of its pivotal connection with the trailer member from the axis of the traction wheels is greater than the distance between the axis of the traction wheels and the rear end of the tractor frame, load-sup-

porting wheels intermediate the ends of the trailer member, and rolling supporting means at the rear end of the trailer member adapted to conform to any movement in a horizontal plane imposed upon it by the tractor member, whereby the tractor member may pull or push the trailer member or swing it laterally while it is supporting a load. 5
